ATTORNEY

UNITED STATES PATENT OFFICE.

EDWARD V. SUNDT, OF CHICAGO, ILLINOIS.

TROUSER SUPPORT.

Application filed September 7, 1923. Serial No. 661,463.

To all whom it may concern:

Be it known that I, EDWARD V. SUNDT, a citizen of the United States, residing at Chicago, in the county of Cook and State of Illinois, have invented new and useful Improvements in Trouser Supports, of which the following is a specification.

This invention relates to a trouser supporting attachment for belt buckles, and an object of the invention is to provide a support structure adapted for attachment to an ordinary belt buckle, which support is designed for engaging the front uppermost button on the fly of the trousers for preventing the sagging of the trousers at the front and consequently eliminate the unsightly appearance caused by the trouser button showing beneath the belt buckle and the consequent sagging of the trousers and the trouser legs. The attachment also prevents the fly of the trousers from wrinkling beneath the belt and also to prevent wear of the cloth caused by contact of the trousers with the coat or vest of the wearer.

Another object of this invention is to provide a belt attachment as specified which will prevent the belt from slipping about the body of the wearer and will also prevent wear on the cloth of the trousers by the edges of the belt buckle.

Other objects of the invention will appear in the following detailed description taken in connection with the accompanying drawings.

Fig. 1 is a perspective view of a belt buckle showing the improved trouser support attached thereto.

Fig. 2 is a section on the line 2—2 of Fig. 1.

Fig. 3 is a cross section on the line 3—3 of Fig. 1.

Referring more particularly to the drawings, a belt buckle 1, of any approved type is illustrated, to the upper and lower edges 45 of which buckle the improved trouser supporting attachment 3 is connected. The attachment 3 has its upper end curved outwardly from the belt buckle as shown at 4, and it is cut away to provide a relatively 50 wide mouth 5 which opens into the channel or slot 6. The slot 6 in turn opens into the substantially circular opening 7. The body of the support 3 about the opening 6 is bulged outwardly as shown at 8 for housing the upper button on the fly of a pair of trousers. The relatively wide mouth 5 to

the opening 6, will permit the button to be properly engaged between the belt buckle 1 and the body of the attachment 3, and the thread used in connecting the button to the 60 trousers will be engaged in the slot 6 permitting the buckle to be adjusted for engaging the button in the outwardly bulged portion 8 which holds the button against accidental disconnection with the body 3. 65

It is, of course, to be understood that the invention may be constructed in other manners and the parts associated in different relations and, therefore, I do not desire to be limited in any manner except as set forth 70 in the claims hereunto appended.

Having thus described my invention what I claim is:—

1. A trouser support comprising a body plate having a substantially centrally disposed opening, and a passageway cut in the plate extending into said opening and terminating in a relatively wide mouth, said body plate being bulged outwardly about 75 said opening.

2. The combination with a belt buckle of a trouser support attached to the buckle at the rear side thereof and comprising a body plate provided with an opening, said body plate being bulged about the major portion 80 of said opening to receive the upper button on the fly of a pair of trousers.

3. A belt buckle comprising a buckle proper, an attachment at the rear of the buckle proper having an opening and a flared channel 90 in communication with the opening, the wall of the opening being disposed to one side of the channel to allow the seating of a button therein.

4. The combination with a belt buckle of 95 a trouser support attached to the buckle at the rear side thereof and comprising a body plate provided with an opening, said body plate being bulged about the major portion 100 of said opening to receive the upper button on the fly of a pair of trousers, said body plate being cut away to provide a slot entering into said first named opening, the outer end of said slot being widened to provide a relatively large mouth or entrance 105 to the slot, the end portions of said body plate being bent transversely to the body plate to space the body plate from the back of the plate.

In testimony whereof I affix my signature.

EDWARD V. SUNDT.
